GOLF PUTTER HEAD WITH HOLDER FOR GOLF BALL AND MARKER

Albert P. Jackson, 2800 Fleur Drive, Building 4,
Apt. 301, Des Moines, Iowa 50321

Filed Jan. 21, 1969, Ser. No. 15,412

Term of patent 14 years

Int. Cl. D21—03

U.S. Cl. D34—5

FIG. 1

FIG. 2

FIG. 3   FIG. 5   FIG. 6

FIG. 7

FIG. 1 is a perspective view of a golf putter head with holder for a golf ball and marker showing my new design,

FIG. 2 is a side view thereof,

FIG. 3 is a top view thereof,

FIG. 4 is a bottom view thereof,

FIG. 5 is a front view thereof,

FIG. 6 is a back view thereof,

FIG. 7 is a fragmentary back perspective view with the dotted line showing of the marker being for illustration only.

I claim:

The ornamental design for a golf putter head with holder for a golf ball and marker, as shown and described.
